US0D1076595S

(12) United States Design Patent (10) Patent No.: US D1,076,595 S
(45) Date of Patent:  May 27, 2025

(54) DISH

(71) Applicant: TURKIYE SISE VE CAM FABRIKALARI ANONIM SIRKETI, Istanbul (TR)

(72) Inventor: Utkan Kozalan, Istanbul (TR)

() Term: 15 Years

(21) Appl. No.: 35/521,804

(22) Filed: Jun. 29, 2024

(80) Hague Agreement Data

Int. Filing Date: Jun. 29, 2024

Int. Reg. No.: DM/238656

Int. Reg. Date: Jun. 29, 2024

Int. Reg. Pub. Date: Aug. 2, 2024

(51) LOC (15) Cl. 07-01

(52) U.S. Cl.

USPC D7/555; D7/560

(58) Field of Classification Search

USPC D7/531, 500, 553.6, 545, 548, 543, 560, D7/555

CPC A47G 23/06; B65D 1/36
